US0D1020375S

(12) **United States Design Patent** (10) Patent No.: **US D1,020,375 S**
(45) Date of Patent: ** Apr. 2, 2024

(54) **LID FOR DRINKING VESSELS**

(71) Applicant: **Liplid AB**, Huddinge (SE)

(72) Inventors: **Håkan Johan Löfholm**, Huddinge (SE); **Lars Bendix**, Randers NÖ (DK)

(73) Assignee: **Liplid AB**, Huddinge (SE)

(**) Term: **15 Years**

(21) Appl. No.: **35/516,398**

(22) Filed: **Dec. 8, 2021**

(80) **Hague Agreement Data**

Int. Filing Date: **Dec. 8, 2021**

Int. Reg. No.: **DM/219680**

Int. Reg. Date: **Dec. 8, 2021**

Int. Reg. Pub. Date: **Jun. 10, 2022**
